UNITED STATES PATENT OFFICE.

GLEN D. FLEAK, OF MUSKOGEE, OKLAHOMA.

WIND-SHIELD CLEANER.

1,217,740.

Specification of Letters Patent. Patented Feb. 27, 1917.

Application filed September 8, 1916. Serial No. 118,991.

To all whom it may concern:

Be it known that I, GLEN D. FLEAK, a citizen of the United States, and a resident of Muskogee, in the county of Muskogee and 5 State of Oklahoma, have invented a certain new and useful Improvement in Wind-Shield Cleaners, of which the following is a specification.

My invention is an improvement in wind-shield cleaners, and has for its object to provide a device of the character specified by means of which a wind-shield may be cleaned from within the auto without the necessity of extending the arm beyond the 15 shelter of the car.

In the drawings:

Figure 1 is a front view of a portion of a wind-shield showing the cleaner in place;

Fig. 2 is an enlarged section on the line 20 2-2 of Fig. 1, looking in the direction of the arrows adjacent to the line.

The present embodiment of the invention is shown in connection with a wind-shield having the usual frame. An arc-shaped or 25 curved supporting member 3 is provided in the form of a split sleeve, the split being wide enough to permit the passage of the frame member 1 of the wind-shield. This member has secured to the inner portion 30 thereof, and at approximately the center, a block of rubber or the like, the said block having the face adjacent to the frame concaved forming a sliding shoe for engaging the frame, and this block is held in place in 35 the split sleeve 3 by means of a clip 5 which is secured to the sleeve.

Clamping plates 6 are pivotally connected with the opposite side edges of the split, as indicated at 7, and each of these clamping 40 plates is normally spring pressed at its upper end toward the other, that is, toward the center of the sleeve by means of a spring 8. These springs are arranged between the plates and the sleeve, and each plate is covered on the face adjacent to the wind-shield with a facing 9 of leather or the like, to prevent scratching of the frame or the glass. Normally the clamping plates occupy the 45 dotted line position of Fig. 2, and it will be evident that when the sleeve is slipped over the frame, the clamping plates will firmly clamp both the frame and glass in such manner that the sleeve will be firmly supported on the frame, yet may be moved from end 50 to end of the shield to permit the cleaning 55 of the same.

A substantially U-shaped bracket 10 is secured to the sleeve opposite to the split, and within this bracket is journaled a shaft 11, the ends of the shaft extending beyond the bracket. A crank 12 is secured to one end of the shaft and a squeegee supporting arm 13 is secured to the other end. Squeegee members 14 and 15 are pivoted to the arm. A facing 16 of rubber or the like is provided for the squeegee members and they are normally pressed into contact with the glass by means of a coil spring 17 which encircles the shaft 11 between a stop 18 adjustably mounted thereon and that end of the bracket 10 adjacent to the arm 13. This spring normally presses the shaft 11 toward the crank 12, that is, toward the interior of the car, making thus firm pressure of the rubber 16 against the glass. 75

In operation, the parts are arranged as shown in Figs. 1 and 2, and when not in use the sleeve 3 may be moved toward one end of the shield. When it is desired to clean the glass, the crank 12 is swung to 80 cause the arm 13 to swing as indicated by the semi-circular dotted line in Fig. 1. The rubber 16 moving firmly in contact with the glass will remove moisture and other accretions therefrom, leaving the same clean. The 85 arrangement may be such that the arm 13 and the squeegee members will swing from one end of the windshield to the other, cleaning thus practically the entire expanse of glass at one operation. The device may be 90 of small relative size, being mounted to move from end to end of the shield and to clean portions thereof in succession.

I claim:

1. A wind-shield cleaner comprising a 95 split supporting sleeve for receiving the frame of the wind shield, clamping plates at the opposite sides of the split for engaging the frame and glass and normally spring pressed toward the frame, a slide shoe with in the sleeve for engaging the top of the frame, a supporting bracket mounted on the sleeve and arranged transverse to the axis thereof, a shaft journaled in the bracket and provided at its inner end with a crank 100 105 and at its outer end with a cleaning arm, and cleaning members in connection with the arm, and a spring normally pressing the

arm toward the glass, said clamping plates being faced with a flexible material.

2. A wind-shield cleaner comprising a split sleeve for receiving the frame of the shield and having spring controlled clamp-
5 ing means for engaging the said frame and the glass, and mounted to slide on the frame,

a crank shaft journaled transversely of the sleeve and provided at the opposite end from the crank with a radial arm having cleaning members, and a spring normally pressing the shaft in a direction to press the cleaning members toward the glass.

GLEN D. FLEAK.
